UNITED STATES PATENT OFFICE.

EDWIN T. GREENFIELD, OF KIAMESHA, NEW YORK.

MACHINE FOR MAKING TUBING.

No. 838,179.

Specification of Letters Patent.

Patented Dec. 11, 1906.

Application filed November 16, 1905. Serial No. 287,695.

To all whom it may concern:

Be it known that I, EDWIN T. GREENFIELD, a citizen of the United States, residing at Kiamesha, in the county of Sullivan and State of New York, have invented certain new and useful Improvements in Machines for Making Tubing, of which the following is a specification.

The object of this invention is to effect certain improvements in machines for making tubing by bending long flexible strips of sheet metal spirally, such tubing being adapted for use in the transmission of a fluid, as water or steam, and as a housing for electric conductors which may be run loosely therein or on the exterior of which the tubing may be formed as armor.

More particularly the invention relates to machines of the type shown in Patent No. 630,502, granted to me August 8, 1899.

My present invention involves so constructing a machine of this type that it may be used for making various sizes of such spirally-formed tubing and making it from strips of various widths. It also involves the provision of improved devices for taking up the tubing as it is formed by the bending mechanism of the machine. It further involves other novel features, all of which will be definitely indicated in the claims appended hereto.

The preferred embodiment of my invention is illustrated in the accompanying drawings, in which—

Figure 1 is a plan view of the machine. Fig. 2 is a sectional elevation of the tubing employed as cable-armor. Fig. 3 is an elevation of a portion of the machine with parts in section. Fig. 4 is a plan view, and Fig. 5 a section on line 5 5 of Fig. 4, of the bending and feeding mechanism on a larger scale. Fig. 6 is an enlarged view of the lower half of the bending-die. Fig. 7 is a view showing the gearing for driving one of the reel-carrying frames. Fig. 8 is a central section through the frame of the take-up reel, the reel being removed therefrom, the plane of the section being indicated by the line 8 8 of Fig. 1 of the frame carrying the reel on which the armored cable or the tube is wound, and Fig. 9 is a sectional detail on line 9 9 of Fig. 8.

Referring to the drawings, A indicates a table mounted on a bed-plate A', and in the sides thereof are bearings for a shaft B, carrying a bevel-gear b and a spur-gear b', to which latter power is communicated in any suitable manner. At the center of the top of the table

is an opening, and concentric therewith are four slots c, Fig. 4. A supporting-plate C rests upon the upper surface of the table, and a cylindrical stem C', depending from the under side thereof, extends through the opening in the top of the table. Bolts c' extend through openings at the corners of the plate C and through the curved slots in the table A, and the ends of these bolts are threaded to receive nuts which may be tightened up to hold plate C securely in any position of adjustment about the axis of stem C'. This angularly-adjustable plate supports the rollers by which the strips of sheet metal are curved transversely and fed forward to the bending-die, and means are provided for driving these rollers in all positions of adjustment of plate C without removing or changing any of the gears or other parts. Stem C' forms a bearing for a double bevel-gear D, Figs. 3 and 5, having teeth meshing with those of gear b on power-shaft B, and also teeth meshing with those of a gear D', carried by a shaft d, mounted in suitable bearings in supports d' d', secured on plate C. Also mounted in bearings in the supports d' d' are two pairs of shafts e, the shafts of each pair being mounted one directly above the other and having at one end intermeshing gears e'. The lower gear e' of each of these pairs meshes with a gear d'', carried by shaft d on the end opposite that on which the bevel-gear D' is mounted. Extending horizontally between the supports d' and between the shafts e of each pair is a trough or chute E, supported on bars e'', secured to the supports d' and arranged to be vertically adjustable by screws e'', Fig. 5. Extending through trough E are two grooves or guides, and on each of the shafts e is a die-roller E', the rollers on each pair of shafts entering openings in the trough E to one of the guides or grooves therein. The peripheries of rollers E' are so shaped that strips of sheet metal passing through the grooves in trough E and between the pairs of die-rollers are given the transverse curvature necessary for making the particular style of tubing desired.

For making the tubing shown in Fig. 2 the periphery of the upper roller entering the right-hand groove is convex and that of the lower one concave, and of the left-hand pair the upper one has a concave and the lower a convex periphery. The periphery of the convex roller of each pair may, if desired, be provided with teeth, as shown in Fig. 5,

which form indentations in the concave side of the strip, since such indentations facilitate the bending of the strip. It will be observed that the axis of stem C', about which the plate C, carrying the trough E and die-rollers E' is angularly adjustable, is coincident with the axis of the gear D, which drives the die-rollers, so that adjusting-plate C, for a purpose hereinafter more fully explained, does not in any way disturb the relation of the gears D and D'.

The forming or bending die F, into which the strips pass from the grooves in trough E and by which they are bent spirally into tubular form, is preferably constructed as shown in my patent above mentioned. The lower half of this die is shown in Fig. 6. The upper half is of similar construction and is provided with dowel-holes to receive the dowel-pins on the lower half. (Shown in Fig. 6.) When the two halves are put together, they form a die having an opening therethrough, which die comprises two sections each consisting of an upper and a lower half. The wall of the opening in the left-hand section of the die has a spirally-formed groove therein presenting a convex face and the right-hand section has a similar groove presenting a concave face. The lower half of each die-section is slotted at its upper edge, so that when the parts of the die are assembled two openings will be provided, each leading to and alining with one of the grooves in the wall of the opening in the die. Of course the shape of these grooves may be changed to make tubing from strips of different cross-section, and the number of sections of the die may be changed with the number of strips from which the tubing is formed. Die F is secured in a support F', which is arranged to slide toward and away from the end of trough E upon a block F², the upper face of which is provided with a dovetail groove into which a corresponding tongue f on support F' extends. The lower face of block F² is provided with a similar dovetail groove at right angles to that on the upper face to receive a tongue f' on table A. The position of die F is thus adjustable in any direction in a horizontal plane, and any suitable means, as screws f² and gib f³, may be provided for locking-support F' and block F² in any adjusted position.

On either side of the mechanism above described is a rotatable frame, that on the left being indicated by the letter G and that on the right by the letter H, in which frames reels G' and H', respectively, are mounted for rotation. When the machine is used for armoring cables or the like, the unarmored cable is unwound from reel G' and after being armored is wound upon reel H'. When the machine is used for making hollow tubing, the frame G and reel G' may be dispensed with, and as such tubing is made it may be

wound upon reel H'. In addition to rotating the reels on their axes to unwind and wind the tubing or cable the reels are turned transverse to their axes, as the sheet-metal strips are bent spirally thereon by rotating frames G and H. On the base A' on opposite sides of table A are standards g g and h h, in which are bearings for the frames G and H, respectively. On the ends of each of these frames are short hollow shafts g' g' and h' h' in axial alinement and extending through the bearings in the standards g g and h h. On the adjacent ends of the hollow shafts g' and h' nearest the die F are gears g² and h², by which rotary motion is communicated to frames G and H from the power-driven shaft B, the ends of which extend through the bearings in the sides of table A and carry pinions b² b². The arrangement of the gearing between each of the pinions b² b² and the corresponding gear g² and h² is shown in Figs. 7 and 8. Pivotaly mounted on the hollow shaft h' between gear h² and the bearing in standard h' is an arm I, carrying at its free end a shaft i, one end of which forms a bearing for a gear i', adapted to mesh with pinion b² on power-shaft B, and the other end of which extends through a curved slot in standard h, concentric with the hollow shaft h'. This end of shaft i is threaded to receive a nut i², which may be tightened up against the standard h, to hold arm I in any adjusted position angularly about the shaft h'. Mounted on arm I is a short shaft forming a bearing for a pinion i³, which meshes with gears h² and i'. This arrangement of gearing is employed in driving both frames G and H, Fig. 3, and it will thus be seen that by loosening nuts i² and turning arms I on their pivots the pinions b² may be removed from shaft B and pinions of different size substituted therefor, whereupon arms I may be again swung around on their pivots and locked in the position in which gears i' mesh with the new pinions b². The construction thus permits of quickly and readily changing the rate of rotation of frames G and H relatively to the rate of rotation of the die-rollers E'. This is necessary when changes are made in the size of tubing to be made, as when such changes are made greater or less lengths of the sheet-metal strips are required for each convolution of the tubing.

The frame G has bearings formed in the sides thereof for the reel G', which carries the cable to be armored. The cable is unwound from the reel and passes through the hollow shaft g' and the forming-die F, where the tubing is spirally formed thereon. From the die the armored cable passes through the hollow shaft h' and is wound upon the reel H'. Means are provided for rotating this reel on its axis at a delicately-adjustable speed to take up the armored cable, such adjustment being of importance on account of differences

in the diameter of tubing made on the machine and the increasing circumference of the roll as the cable is wound thereon. The mechanism for effecting this rotation of reel 5 H' is best shown in Figs. 8 and 9. In the sides of frame H are bearings for trunnions J , in each of which is an opening of square cross-section, and a square rod J' extends through these openings and similar ones in 10 the sides of the reel H' . In this way the reel and the trunnions J must turn together, and by removing the rod J' the reel can be taken out. Secured to each of the trunnions J is a 15 ratchet-wheel j , and rotatable upon each of the trunnions between the ratchet-wheel and the sides of frame H are pawl-plates j' , each having an extension j^2 at one side and at the other having pivoted thereto four actuating-pawl 20 j^3 , which are pressed by suitable springs, as at j^4 , upon the teeth of ratchet j . The pawls j^3 on each plate j' are so positioned that when the first one is at the bottom of a tooth of the ratchet the succeeding ones are at progressively-increased distances up the 25 inclined sides of other teeth. Pivoted to each of the sides of frame H are four retaining-pawl k , similarly pressed by springs, as at k' , upon the periphery of a ratchet j . The four pawls k on each side of the frame are also 30 staggered with relation to the teeth of the ratchet on which they bear, so that one of them is always in position to prevent backward rotation of the reel H' . Each of the pawl-plates j' is turned back and forth on its 35 trunnion J by a rod m , extending through an opening in the extension j^2 of the plate and also through openings in a member m' . Nuts are provided on the ends of rod m to prevent it from moving out of those openings, and between extension j^2 and member m' a spring m^2 is coiled upon rod m . Secured to the member m' is a rod n , movable in suitable guides n' on the side of frame H , a spring n^2 being coiled about the rod between one of the 40 arms of member m' and one of the guides n' to press rod n in a direction to cause a roller o on the end thereof to engage a cam o' , shaped as shown in Figs. 1 and 8. This cam is supported on the end of an interiorly-threaded sleeve p , mounted for longitudinal movement in a cylindrical opening in a plug p' , which is secured to the standard h and extends into the end of the hollow shaft h' . Turning of sleeve p is prevented by wings p^2 , 45 secured to the sleeve and extending into longitudinal grooves in the plug p' . A shaft s extends through plug p' , and its inner threaded end enters the threaded bore in sleeve p . Shaft s is positioned by a collar s^2 thereon and 50 a hand-wheel s' , which is secured to its outer end. Thus by turning wheel s' the sleeve p and cam o' are moved in or out to vary the portion of each half-revolution of the frame in which the roller o is in contact with the 55 cam o' , and thus vary the distance through

which rods m and n are reciprocated. As the reciprocation of these rods governs the angular movement of the pawl-plates j' on trunnions J , the latter can by the adjustment of hand-wheel s' be made such that one, two, 70 three, or all four of the staggered pawls j^3 on each side of reel H' fall over teeth of a ratchet j each time to vary the extent of rotational movement of reel H' in each half-revolution of frame H .

In operating the machine to armor electric cable a reel of unarmored cable is mounted upon the frame G and its end threaded through the hollow shaft g' and the bending-die F . The ends of two long flexible strips 80 of sheet metal (preferably steel) are inserted in the grooves in trough E and between the pairs of die-rollers E' . The die-rollers are rotated by power applied to gear b' on shaft B by means of gears b , D , and D' , shaft d , 85 gear d^2 , and gears e' on the shafts e , carrying the die-rollers. The die-rollers on the left of Fig. 1 bend the strip passing between them to give it a transverse curvature such that the convolutions of the tubing formed therewith present a concave outer surface, as shown in Fig. 2, and they indent the concave face of the strip so that it may be formed spirally more readily; also, the rollers force the strip forward through the opening in the 90 forming-die F and against the bending-surface thereof. The pair of die-rollers on the right in Fig. 1 act similarly on the other strip except that they curve the strip transversely in the opposite direction. As the strips are 95 forced into the die by the rollers E' , the spirally-formed convex and concave surfaces on the forming-die bend the two strips spirally closely around the cable and one over the other and breaking joints therewith, 100 as shown in Fig. 2. As the die-rollers E' are actuated by shaft B the frames G and H carrying the reels G' and H' , respectively, are rotated to turn the strand of cable extending between them on its axis, and the rate at 105 which it is turned is the same as the rate of forming the convolutions of the tubing. The rotation of the reel-carrying frames is effected by means of the pinions b^2 on shaft B , gears i' , pinions i^3 , and gears g^2 and h^2 on the shafts g' and h' of frames G and H , respectively. The armored cable is wound upon the reel H' , which is automatically rotated on its axis as the frame H , which carries it, is rotated on its shafts h' h' . This is effected 110 by the circular cam-surface o' , having two raised portions thereon over which the rollers o move as the frame H is rotated. Cam o' , though movable toward and away from the rod J' of reel H' by turning hand-wheel s' , is held against rotation as frame H rotates by the wings p^2 , extending into the slots in the stationarily-mounted plug p' , and therefore as frame H rotates cam o' causes a reciprocation of rods n and m in guides n' , 130

and thus turns pawl-plates j' back and forth on trunnions J . One or more of the pawls j^3 drop over the teeth of ratchet j when the plates j' are moved by cam o' , and when the plates are moved in the opposite direction by springs n^2 after rollers o have passed over the highest points on the cam-surface the pawls thereon turn reel H' a definite portion of a revolution, and in the position to which it is moved the reel is held by the retaining-pawl k . The backward movement of plates j' by springs n^2 is limited by the engagement of one of the arms of member m' and one of the guides n' , so that when cam o' has been moved by wheel s' to the retracted position the rollers o bear on cam o' for only very small portions of a revolution, and therefore the movement of rods m and n and plates j' each half-revolution of frame H is very small, so small that only one of the four staggered pawls on each side of reel H' drops over a tooth of the ratchet j . By turning wheel s' the cam o' is advanced from this position to cause any desired number of the four pawls to drop over teeth of the ratchets. In this way the speed of rotation of reel H' can be adjusted while the machine is in operation and frame H rotating, such adjustment being necessary to take up the armored cable properly on account of the increasing diameter of the reel as the cable is wound thereon.

It is frequently necessary to change the angular arrangement of the trough E and the die-rollers E' relative to the die F —as, for instance, when tubing of a different diameter is to be made, when a different width of metallic strip is to be used, or a different character of tubing is desired. In a machine constructed in accordance with my invention this can be quickly done without any change in the gearing. The trough E , die-rollers E' , and driving-gearing for the latter are all carried on a supporting-plate C , which is adjustable about an axis coincident with the axis of the gear D by which the rollers E' are driven, so that to change the angular relation of trough E with respect to die F it is only necessary to loosen the nuts on bolts c' , turn plate C about the axis of stem C' to the desired position, bolts c' moving in the slots c in table A , and then tighten the nuts up again to hold the plate in its new position. In doing this the gear D' rolls around on the gear D , but the driving relation of gear D to gear D' , and hence to the die-rollers E' , is in no way disturbed. The die F may then be properly positioned with respect to the end of trough E by loosening screws f^2 and moving support F' on block F^2 and block F^2 on table A and again tightening the screws when the die is in the proper position. Also the trough E may be adjusted vertically by means of the screws e^3 .

When tubing of a different diameter is to be made with strips of the same width, the rate of rotation of the reel-carrying frames G

and H relative to that of the die-rollers E' must be changed, since a greater length of strip is required for each convolution of the tubing. Such changes can readily be made by loosening nuts i^2 , swinging arms I on their pivots to carry gears i' away from pinions b^2 , shafts i moving in the curved slots in the standards, removing pinions b^2 from shaft B and replacing them with pinions of a different size, then swinging arms I back on their pivots to bring gears i' properly into mesh with the new pinions b^2 , and locking the arms in this position by tightening up nuts i^2 .

It will be understood that the adjustable die-rollers, the driving mechanism arranged to drive the die-rollers in any position of their adjustment without any change in the gearing, and the improved means for rotating the reel upon which the completed tubing is wound may be used with spirally-forming means of different character from that shown.

Having now described my invention, what I claim as new therein, and desire to secure by Letters Patent, is as follows:

1. The combination of a movable die adjustable about an axis, means for bending a strip after it has been acted upon by said die, and driving mechanism for actuating said die arranged to permit adjustment of the die without affecting the driving relation of said mechanism, substantially as described.

2. The combination of a movable die, a support therefor adjustable about an axis, means for bending a strip spirally after it has been acted upon by said die, a power-driven shaft, and gearing connecting said shaft in driving relation to said die and arranged to permit adjustment of the die without affecting the driving relation of said gearing, substantially as described.

3. The combination of a support adjustable about an axis, means for locking the support in any adjusted position, rotatable die-rollers mounted on the support, means for bending a strip spirally after it has been acted upon by said die-rollers, and gearing for driving said die-rollers arranged to permit adjustment of said support without affecting the driving relation of said gearing, substantially as described.

4. The combination of a support adjustable about an axis, a pair of rotatable die-rollers carried thereby, means for bending a strip spirally after it has been acted upon by said die-rollers, a rotatable frame, a reel mounted for rotation therein, a power-shaft, and means for connecting said shaft in driving relation to said die-rollers and said frame permitting adjustment of the support carrying the die-rollers without affecting the driving relation of said gearing, substantially as described.

5. The combination of a support adjustable about an axis, a movable die mounted thereon, a member mounted for rotation on

said axis, driving mechanism therefor, means connecting said member in driving relation to said die, and means for bending a strip after it has been acted upon by said die, substantially as described.

5 6. The combination of a support adjustable about an axis, a plurality of die-rollers mounted for rotation in bearings thereon, a gear mounted for rotation on said axis, driving mechanism therefor, gearing meshing with said gear and connecting it in driving relation to said die-rollers, and means for bending a strip spirally after it has been acted upon by a die-roller, substantially as described.

10 7. The combination of a support, a trough having an opening extending longitudinally therethrough mounted upon the support, means for adjusting the position of the trough on the support, means for effecting a transverse curvature of a strip in passing through the opening in said trough, and means located in proximity to the end of the trough for bending a strip spirally, substantially as described.

15 8. The combination of a support adjustable about an axis, a trough having an opening extending longitudinally therethrough mounted upon the support, means for adjusting the position of the trough on the support, a pair of die-rollers mounted for rotation in bearings on the support and extending through slots in the sides of said trough to the opening therethrough, mechanism for driving said die-rollers permitting adjustment of said support without affecting the driving relation of said mechanism, and means located in proximity to the end of said trough for bending a strip spirally, substantially as described.

20 9. The combination of a die for effecting a transverse curvature of a strip, a bending-die for bending the strip spirally after it has been acted upon by said die, a support upon which said bending-die is adjustably mounted, and means for locking the bending-die in any position of adjustment, substantially as described.

25 10. The combination of a support, a trough thereon having a longitudinal opening therethrough, means for effecting a transverse curvature of a strip while passing through said opening, a bending-die in proximity to the end of said trough, a support for the bending-die, means permitting adjustment of the bending-die on its support in one direction and in a direction at right angles thereto, and means for locking the bending-die in any adjusted position, substantially as described.

30 11. The combination of a support adjustable about an axis, means for locking the support in any adjusted position, rollers mounted for rotation in bearings on said support, mechanism for driving said rollers permitting adjustment of said support without

affecting the driving relation of said mechanism, a bending-die for bending a strip spirally after it has been acted upon by said rollers, means for supporting said bending-die permitting adjustment thereof with respect to said rollers, and means for locking said bending-die in any adjusted position, substantially as described.

35 12. The combination of a support adjustable about an axis, a pair of die-rollers mounted for rotation in bearings on said support for effecting a transverse curvature of a strip, a member mounted for rotation on the axis of adjustment of said support, driving mechanism therefor, means connecting said member in driving relation to said die-rollers, a bending-die for bending a strip spirally after it has been acted upon by said die-rollers, means for supporting said bending-die permitting adjustment thereof with respect to 85 said die-rollers, and means for locking the bending-die in any position of adjustment, substantially as described.

40 13. The combination of mechanism for bending a strip spirally, a movable member 90 acting upon the strip before it is bent spirally, a power-shaft, means connecting the power-shaft in driving relation to said member, a rotatable frame, a reel to receive the spirally-formed strip mounted for rotation in 95 said frame, gearing connecting the power-shaft in driving relation to said frame, and means to facilitate changing the ratio of the rates at which the power-shaft actuates said member and said rotatable frame, substantially as described.

45 14. The combination of a pair of rollers between which a strip passes, a power-shaft, means connecting the shaft in driving relation to said rollers, means for bending the strip spirally after it has been acted upon by said rollers, a rotatable frame, a reel to receive the spirally-formed strip mounted for rotation in said frame, and means connecting the power-shaft in driving relation to said 105 rotatable frame comprising gears on the power-shaft and the shaft of the frame, an arm pivoted on one of said shafts, a gear carried by said arm and serving to connect said gears, and means to lock said pivoted arm in 110 any adjusted position, substantially as described.

50 15. The combination with means for forming spiral tubing, of a rotatable frame on one side thereof, a freely-rotatable supply-reel 120 journaled therein, a rotatable frame mounted on the other side of said means, a take-up reel mounted for rotation in said last-named frame, means for rotating said take-up reel, and means for adjusting the speed of 125 rotation of said take-up reel independently of that of its frame, substantially as described.

55 16. The combination of means for bending a strip spirally into a tube, means for feeding 130

- a strip to said bending means, a rotatable frame on one side of said bending means, a freely-rotatable supply-reel journaled therein, a rotatable frame on the opposite side of said means, a reel upon which the spirally-formed tube is wound mounted for rotation on said last-named frame, and means for rotating said last-named reel by a step-by-step movement, substantially as described.
10. 17. The combination with means for forming spiral tubing, of a freely-rotatable frame on one side of said means, a supply-reel journaled therein, a rotatable frame on the opposite side of said means, a take-up reel for said tubing journaled in the last-named frame, means for rotating the last-named reel by a step-by-step movement, and means for adjusting the speed of rotation of said last-named reel, substantially as described.
15. 18. The combination with means for forming spiral tubing, of a rotatable frame, a take-up reel mounted for rotation thereon, a pawl-and-ratchet mechanism actuated by the rotation of said frame for rotating said reel, and means for adjusting said mechanism to adjust the speed of rotation of said reel, substantially as described.
20. 19. The combination with means for form-

ing spiral tubing, of a rotatable take-up reel for said tubing, a ratchet-wheel secured to said reel, a pawl-plate, a plurality of pawls carried thereby and staggered relatively to the teeth of the ratchet, springs pressing the pawls in engagement with the teeth of the ratchet, means for reciprocating said pawl-plate, and means for adjusting the limits between which the pawl-plate is reciprocated, substantially as described.

20. The combination with means for forming spiral tubing, of a rotatable frame, a take-up reel for said tubing mounted for rotation on said frame, driving mechanism for rotating said frame, and means for rotating said reel comprising a pawl and a ratchet, one mounted on the reel and the other on the frame, and a cam and co-operating member for actuating the pawl and ratchet, one carried by the rotatable frame and the other mounted stationarily, substantially as described.

This specification signed and witnessed this 14th day of November, 1905.

EDWIN T. GREENFIELD.
